UNITED STATES PATENT OFFICE.

FRANCIS B. ALLDREDGE, OF DES MOINES, IOWA.

DETACHABLE-END BAILER.

1,389,023.

Specification of Letters Patent. Patented Aug. 30, 1921.

Application filed October 18, 1920. Serial No. 417,791.

To all whom it may concern:

Be it known that I, FRANCIS B. ALLDREDGE, a citizen of the United States, and a resident of Des Moines, in the county of Polk 5 and State of Iowa, have invented a certain new and useful Detachable-End Bailer, of which the following is a specification.

The object of my invention is to provide a detachable end bailer of simple and inexpensive construction.

In bailing the water, sand and other material from deep holes, such as oil and gas wells, it is common to use a comparatively long, deep bailer of relatively small diameter and great difficulty has been experienced in cleaning out the bailer when mud, sand and stones fill up the lower part of the bailer and settle there during the drawing of the bailer from the hole.

It is my object to obviate the difficulty just mentioned by providing a bailer, having a lower end, which is readily detachable, and yet which can be used in the ordinary way with the ordinary machinery for removing water, sand and stones from such a hole.

With these and other objects in view, my invention consists in the construction, arrangement and combination of the various 30 parts of my device, whereby the objects contemplated are attained, as hereinatfer more fully set forth, pointed out in my claims, and illustrated in the accompanying drawings, in which:

Figure 1 shows a side elevation of a bailer, embodying my invention, parts being broken away and parts being shown in section, the bailer body and the detachable lower end being shown separated and in their positions 40 just before being united.

Fig. 2 shows a vertical, central, sectional view through the lower part of the bailer, after the body and the bottom have been connected together.

Fig. 3 shows a horizontal, detail, sectional view taken on the line 3—3 of Fig. 2.

Fig. 4 shows a detail, sectional view taken on the line 4—4 of Fig. 2; and

Fig. 5 shows a vertical, sectional view 50 taken on the line 5—5 of Fig. 2.

In drilling oil and gas wells and similar deep holes, it is well-known that after certain depths are reached, water will flow into the hole and carry with it small stones

and sand. It frequently becomes necessary 55 in the drilling of such holes to bail out the water and the small stones and sand, and the practice commonly followed is to use a tall slender bucket commonly called a bailer, having a flap valve or the like at the bottom.

The rock in the hole is crushed or broken up with the drill and water is then poured into the hole, so that the stone may be taken out with the water by means of the bailer. 65 The bailer is sometimes from thirty to forty feet long.

The bailer is lowered into the hole, filled through the bottom and then pulled out. Frequently mud, sand and small stones collect in the bottom of the bailer, and when the bailer is withdrawn from the hole, it is a matter of considerable difficulty to remove the more or less solid contents at the bottom of the bailer. It is sometimes necessary to 70 invert this long bailer and jar it and pound it to remove its contents.

To obviate the difficulty of such removal and to facilitate the speed with which such removal can be accomplished, I have provided a bailer with a removable bottom.

My invention may be embodied in a considerable variety of forms. In the particular form illustrated in my drawings, which accompany this application, I have used the 85 reference numeral 10 to indicate generally the body of the bailer, having the form of a cylinder.

At the lower end of the body 10, there is provided a reduced portion 11, which may 90 be made integral with the body 10 or may be in the form of a sleeve or the like welded or otherwise secured to the body 10.

The detachable bottom of my bailer comprises a cylindrical member 12, having a 95 bottom provided with a flap valve 13, having a downwardly projecting member 14, which is of ordinary construction, and in itself forms no part of my invention. The detachable bottom member 12 is provided on 100 its interior with inwardly projecting lugs 15. In the particular form of my device herein illustrated, I have shown three of the lugs 15 arranged at the same height and spaced equi-distantly around the bottom 105 member 12. The shape of the lugs 15, as viewed from the inside of the bailer bottom 12, is illustrated especially in Fig. 5.

The upper and lower surfaces of the lugs 15 are preferably parallel, and preferably both of said surfaces are inclined from the horizontal, as illustrated in Fig. 5. One end 5 of each lug 15 is beveled as at 16.

In the upper edge of the bottom member 12 is a notch 17 above each lug 15. In the reduced portion 11 are formed grooves or channels 18 open at their lower ends at the lower 10 edge of the reduced portion 11, preferably formed by pressing the wall of the portion 11 inwardly. The side walls of the channels 18 are then machined out, so that said grooves or channels are wider 15 at their bottoms than at their outer portions.

Slidably mounted in each channel 18 is a key 19, having at its upper end, a horizontal flange or lip 20, projecting outwardly from between the walls of the channel 18. 20 The lower portion of each key 19 is beveled at one side, as at 21, to correspond to the beveled end 16 of the lug 15, for a purpose which will be hereinafter more fully explained.

25 The channels 18 and the body of the portion 11 are provided at points spaced upwardly from the lower edge of the portion 11 with slots 22, which are inclined from the horizontal, and are designed to receive 30 the lugs 15, when the bailer body and the detachable bottom member are connected together.

Assuming, that the parts are completed and assembled, excepting for the connecting 35 of the bailer body and the removable bottom, and assuming that the keys 19 are at the upper positions of their movement, I will now described the method of connecting the removable bottom 12 with the body 40 of the bailer.

It will, of course, be understood that the 45 keys 19 slide longitudinally of the bailer in the channels 18. The thickness of the walls of the bottom member 12 is preferably the same as the thickness of the walls of the bailer body 10, and the outside diameters of the bottom member and the bailer body are the same.

The external diameter of the reduced 50 portion 11 is such that the portion 11 may be snugly inserted into the upper portion of the removable bottom member 12. The removable bottom member 12 is slid over the reduced portion 11 with a movement longitudinal of the bailer and with the lugs 15 sliding in the channels 18. When the lugs 15 reach the notches or slots 22, the bottom member 12 is rotated with relation to the body 10 for causing the lugs 15 to slide 60 into the slots 22.

It will be understood in this connection 65 that the slots 22 are of such size, as to snugly receive the lugs 15, and it will be noted that the rotation of the bottom member with relation to the body of the bailer

for sliding the lugs 15 into the slots 22 will cause the bottom 12 to be slid longitudinally somewhat with relation to the body of the bailer on account of the inclined shape of the slots 22 and the lugs 15.

I preferably provide a gasket 23 at the upper end of the bottom 12 and between such upper end and the shoulder formed at the lower end of the body portion 10, as illustrated for instance in Fig. 2. Such 75 shoulder and the upper end of the member 12 or either of them are preferably beveled or grooved, so that the gasket 23 may be received and practically hidden, when the members 12 and 10 are forced together.

80 After the bottom member 12 has been rotated a sufficient distance to permit the downward movement of the keys 19, such keys are forced downwardly with their beveled edges 21 in engagement with the beveled edges 16 of the lugs, and it will be seen that the forcing of the keys downwardly will force the lugs 15 farther into the slots 22, and will, of course, on account of the peculiar shapes of the slots 22 and lugs 15 90 tighten the joint at the gasket between the bottom 12 and the body 10 of the bailer.

95 In this connection it may be mentioned that during such downward sliding movement of the keys 19, the flanges 20 enter the slots 17.

100 It should perhaps be mentioned that the slots 17 are of sufficient width to permit the proper rotation of the bottom 12 with relation to the body of the bailer when the keys 19 are traveling downwardly and after the flanges 20 have entered the notches 17.

105 When the keys 19 are thus in their lower positions, a tight joint will have been made between the bailer body and the removable bottom, and such tight joint can be maintained after considerable wear on the parts on account of the use of the beveled faces, hereinbefore described.

110 The bailer when completed has a smooth outside edge, so that it may be dropped into the hole and removed therefrom in the same way, as an ordinary bailer.

115 When the bailer is in use and has been drawn full from the oil or gas well or the like, it may be emptied in the ordinary way. If, however, dirt, mud, sand or stones might have collected in the bottom of the bailer, until it is difficult to remove them, the keys 19 may be forced upwardly by using any 120 suitable instrument for driving the flanges 20 upwardly, and after the lower portions of the keys have cleared the lugs 15, the bottom 12 may be rotated with a motion the reverse of its rotary movement hereinbefore described, until the lugs 15 slide out of the slots 22, whereupon the removable bottom 12 may be pulled off the body of the bailer, and the more or less solid contents of the bailer may then be easily re- 125 130

moved. After this, the bailer parts may be again connected in the manner hereinbefore described.

It will, of course, be obvious that many changes may be made in the details of the construction of my improved detachable end bailer. The side walls of the channels 18 near the slots 22 may be reinforced by welding material thereto, as at 24. The locking device may be varied in quite a number of particulars, and in general I recognize the possibility of varying the details of my construction, and it is my purpose to cover by the claims hereinafter set forth, any such modifications of structure or use of mechanical equivalents, as may be reasonably included within the scope of such claims.

I claim as my invention:

1. A detachable end bailer, comprising a bailer body, a bailer bottom member having an open end and a valve controlled end, a reduced member on said body adapted to be inserted within the open end of the bottom member, having open-ended channels formed therein, the walls of said channels and the walls of said reduced portion having inclined slots, inclined lugs on the interior of said bottom member adapted to slidably enter said channels and to enter said slots when the bottom member is rotated with relation to said body, and bevel-

eled keys slidably received within said channels, said lugs having beveled edges for co-acting with said keys.

35

2. In a detachable end bailer, a bailer member, a second bailer member, a reduced portion on one of said members, having open-ended channels, and having inclined slots extending from said channels into the wall of said portion, the other of said members having on its interior beveled surfaces for coacting with said inclined slots and with keys and keys slidably mounted in said channels, having beveled faces for coacting with said lugs.

40

3. In a detachable end bailer, a bailer member, a second bailer member, a reduced portion on one of said members, having open-ended channels, and having inclined slots extending from said channels into the wall of said portion, the other of said members having on its interior beveled surfaces for coacting with said inclined slots and with keys, keys slidably mounted in said channels, having beveled faces for coacting with said lugs, and a gasket received between said members and adapted to be gripped when one of said members is rotated with relation to the other for forcing said lugs into said slots.
